US0D1036429S

(12) **United States Design Patent** (10) **Patent No.:** **US D1,036,429 S**
(45) **Date of Patent:** ** *Jul. 23, 2024

(54) **ELECTRONIC DEVICE**

- (71) Applicant: **Samsung Electronics Co., Ltd.**, Suwon-si (KR)
- (72) Inventors: **Seo Lee**, Suwon-si (KR); **Seungchan Lee**, Suwon-si (KR); **Sangchulmatt Lee**, Suwon-si (KR); **Hoon Han**, Suwon-si (KR); **Yunjeong Ji**, Suwon-si (KR); **Seonkeun Park**, Suwon-si (KR); **Duyeong Choi**, Suwon-si (KR)
- (73) Assignee: **SAMSUNG ELECTRONICS CO., LTD.**, Suwon-si (KR)
- (*) Notice: This patent is subject to a terminal disclaimer.
- (**) Term: **15 Years**
- (21) Appl. No.: **29/903,657**
- (22) Filed: **Sep. 26, 2023**

(57) **CLAIM**

We claim the ornamental design for an electronic device, as shown and described.

DESCRIPTION

FIG. 1 is a front perspective view of an electronic device showing our new design.

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an enlarged view of the encircled portion in FIG. 1;

FIG. 9 is an enlarged view of the encircled portion in FIG. 1; and,

FIG. 10 is an enlarged view of the encircled portion in FIG. 3.

(Continued)

The short dash-dash broken lines in the figures illustrate portions of the electronic device that form no part of the claimed design. The dot-dot-dash broken lines encircling portions of the claimed design that are illustrated in enlargements form no part of the claimed design.

1 Claim, 10 Drawing Sheets

Related U.S. Application Data

is a division of application No. 29/763,658, filed on Dec. 23, 2020, now Pat. No. Des. 964,336.
